UNITED STATES PATENT OFFICE.

LEON L. RUSSELL, OF NEW ROCKFORD, NORTH DAKOTA.

EXPLOSION-MOTOR.

1,247,156.

Specification of Letters Patent. Patented Nov. 20, 1917.

Application filed November 2, 1915. Serial No. 59,252.

To all whom it may concern:

Be it known that I, LEON L. RUSSELL, a citizen of the United States of America, and resident of New Rockford, in the county of 5 Eddy and State of North Dakota, have invented certain new and useful Improvements in Explosion-Motors, of which the following is a specification.

This invention relates to explosive engines and particularly to rotary valves for controlling the delivery of the explosive charge to the cylinders of a motor and exhausting the gases therefrom after the explosion:

15 An object of this invention is to provide a rotary valve so incased as to be freely rotatable in the casing and so arranged with relation to the said casing that pressure on the said rotating member will be equalized 20 on two sides, a condition which will prevent undue friction of the parts, or binding while the valve is rotating.

A further object of this invention is to provide a combined exhaust duct or pipe and 25 valve casing, the same being coupled with the heads of cylinders in such a way as to make them readily demountable so that the interior structures may be accessible for all purposes.

30 A still further object of this invention is to provide a valve having ports of such a structure or configuration as to insure efficiency in the delivery of the charge and permitting a rapid exhaust of the spent gases 35 or products of combustion.

With the foregoing and other objects in view, the invention consists in the details of construction, and in the arrangement and combination of parts to be hereinafter more 40 fully set forth and claimed.

In describing the invention in detail, reference will be had to the accompanying drawings forming part of this specification wherein like characters denote corresponding 45 parts in the several views, and in which—

Figure 1 illustrates a view in elevation partly in section, showing the motor with the invention applied thereto;

50 Fig. 2 illustrates a sectional view on the line 2—2 of Fig. 1; and

Fig. 3 illustrates a sectional view on the line 3—3 of Fig. 1.

In these drawings 5 denotes the cylinders 55 of a motor which may be applied to any crank casing 6, the exact construction of

these parts being immaterial and therefore are not described in detail. There is a crank shaft or other driving device 7 provided with a valve driving connection and for convenience of illustration, the sprocket chain 8 is shown as engaging the sprocket wheels 9 and 10, the latter of which is on the valve shaft 11 so that the valve shaft is positively driven through a coupling 11^a and it may be 65 coupled and properly timed with relation to the drive shaft 7. It is the desire of the inventor that the showing of the means for driving the valve shaft be regarded as only a conventional illustration and these features may include any well known or preferred connection or gearing for accomplishing the result. 70

The valve casing 12 for each cylinder preferably constitutes a part of the head of 75 the cylinder, the head being indicated by the numeral 13, there being ports 14 leading from the valve casing to the cylinder, one port being shown on each side of the said casing.

80 The rotary valve comprises the side disks 15 and 16 mounted on a section of a hollow shaft 17, that portion of the hollow shaft between the disks being cut away to form an aperture 18 by which the explosive charge 85 enters the valve casing.

The space between the two disks is partially inclosed by radially extending walls 19 and 20 connected to the shaft on each side of the opening 18 and extending to the 90 periphery of said disks. The outer ends of these walls are connected by a plate or wall 21 forming with the said radial walls a flared port through which the explosive charge passes from the tubular shaft. The 95 sides of the rotary valve have apertures 22 of irregular contour, each of said apertures having its outer wall curved so that it is parallel with the periphery of said disk. The side walls of each aperture are convexed and merge with the inner wall which is likewise convexed, thus giving to the walls of the aperture an irregular outline in which the area of the aperture increases gradually from the side edges to the center, 100 a construction which has been found efficient in admitting the explosive charge to the ports 14 to the best advantage. The rotary valve is suitably packed so that the explosive charge cannot escape from the portion of the valve just described except when 105 the apertures of the valve register with the

110

ports 14 and this insures proper delivery of the explosive charge to the cylinder.

As a means for effecting an exhaust from the cylinders, each rotary valve has its sides 5 provided with apertures 23 and when these apertures come into registry or alinement with the ports 14, the exhaust is effected and said exhaust escapes to the exhaust pipe 24 which may be superimposed with relation to 10 the valve casing or may form a part thereof according to the ideas of the producer.

By reason of the fact that there is a very large area of the valve devoted to the exhausting of the gases, it has been found that 15 a very rapid exhaust is effected and that back pressure is eliminated. The shape of the apertures 23 for the exhaust is practically the same as the apertures for the intake of the explosive charge and the same 20 advantages with relation to the rapidity of the passage of the charge and exhaust have been observed to exist.

As a means for admitting the explosive charge to the hollow shaft, the intake manifold 25 has its branches terminating in sleeves 26 and the shafts are rotatable in the said sleeves. There is a coupling 27 between the ends of the shafts in each sleeve and this coupling has ports 28 for the admission of 30 the explosive charge so that said explosive charge passes from the intake manifold to the sleeve and to the coupling, from whence it finds its way into the hollow shaft and the rotary valve.

35 It is believed that a résumé of the operation of the device is unnecessary in view of the fact that the functions of the several parts have been ascribed to them during the description of the said parts, and it follows 40 that if the valves are suitably rotated and an explosive charge is delivered to the intake manifold, the said charge will be delivered to the cylinders and that upon ignition of the charge, the exhaust will be effected through the apertures and ports and 45 the exhaust manifold, as stated. It will furthermore be apparent that there will be equal pressure on the surfaces of the disks forming part of the valve to obviate undue friction or binding of the parts.

I claim

1. In an explosion motor, cylinders, valve casings having ports communicating with the cylinders, a rotary valve in each casing, 55 said rotary valves each comprising disks spaced apart, tubular shafts on which the disks are mounted, each of said shafts having an opening communicating with the interior of the valve casing between the disks, 60 partitions between the disks of each valve forming a duct, said disks having apertures therein to permit the escape of a charge from said duct when said apertures align with the ports of the valve casing, said disks 65 having apertures to align with said ports

for the exhaust of the spent gases, couplings between the hollow shafts, and means for delivering explosive charges to the said couplings.

2. In an explosion motor, cylinders, valve 70 casings having ports communicating with the cylinders, a rotary valve in each of said casings, said rotary valves each comprising disks spaced apart, tubular shafts on which the disks are mounted, each of said shafts 75 having an opening communicating with the interior of the valve casing between the disks, partitions between the disks of each valve forming a duct, said disks having apertures therein to permit the escape of a charge 80 from said duct when said apertures align with the ports of the valve casing, said disks having apertures to align with said ports for the exhaust of the spent gases, couplings between the hollow shafts, means for de- 85 livering explosive charges to the said couplings, and means for rotating the hollow shafts.

3. In an explosion motor, cylinders, valve casings forming the heads of said cylinders, 90 said valve casings having ports communicating with the cylinders, rotary valves in the said casings, each of said valves comprising disks spaced apart, hollow sectional shafts on which said disks are mounted, said shafts 95 having apertures therein discharging between the said disks, radial partitions, a plate connecting the ends of the walls and forming a duct, the disks having apertures therein for the escape of an explosive charge 100 from the said duct, the walls of said apertures being of irregular contour, the outer wall of each aperture being parallel with the periphery of the disk and the side and inner walls thereof being convexed, the said 105 apertures being adapted to align with the ports of the valve casing, said disk having exhaust apertures adapted to align with said ports, means for rotating the shafts, and means for delivering an explosive charge to 110 the sectional shaft.

4. In an explosion motor, cylinders, valve casings forming the heads of said cylinders, said valve casings having portions communicating with the cylinders, rotary valves in 115 the said casings, each of said valves comprising disks spaced apart, hollow sectional shafts on which said disks are mounted, said shafts having apertures therein discharging between the said disks, radial partitions, a plate connecting the ends of the walls and forming a duct, the disks having apertures therein for the escape of an explosive charge from the said duct, the walls of said apertures being of irregular contour, the outer wall of each aperture being parallel with the periphery of the disk and the side and inner walls thereof being convexed, the said apertures being adapted to align with the ports of the valve casing, said 120 125 130

disk having exhaust apertures adapted to align with said ports, means for rotating the shafts, couplings between the sections of the shaft, apertures therein for admitting an explosive charge to the shaft, and means for delivering an explosive charge to the said coupling.

In testimony whereof, I affix my signature in the presence of two witnesses.
